CLAIM

The ornamental design for a portable vaporizer chamber, as shown and described.

DESCRIPTION

FIG. 1 is a perspective view of a portable vaporizer chamber;
FIG. 2 is a front view thereof;
FIG. 3 is a rear view thereof;
FIG. 4 is a right view thereof;
FIG. 5 is a left view thereof;
FIG. 6 is a top view thereof;
FIG. 7 is a bottom view thereof;
FIG. 8 is a bottom perspective view thereof;
FIG. 9 is a front view thereof, showing the plane upon which a cross-sectional view is taken and shown in FIG. 10; and,
FIG. 10 is a side cross-sectional view thereof taken along line 10-10 of FIG. 9.
